UNITED STATES PATENT OFFICE.

JOHN D. RIPSON, OF ROCHESTER, AND ERICK G. SAMPSON, OF JAMESTOWN, NEW YORK,
ASSIGNORS TO ART METAL CONSTRUCTION COMPANY, OF JAMESTOWN, NEW YORK, A
CORPORATION OF NEW YORK.

SUSPENSION FOR DRAWERS FOR CABINETS, &c.

No. 884,596.

Specification of Letters Patent. Patented April 14, 1908.

Application filed October 28, 1907. Serial No. 309,888.

To all whom it may concern:

Be it known that we, JOHN D. RIPSON, a resident of Rochester, in the county of Monroe and State of New York, and ERICK G. SAMPSON, a resident of Jamestown, in the county of Chautauqua, State of New York, have invented a new and useful Improvement in Suspensions for Drawers for Cabinets, &c.; and we do hereby declare the following to be a full, clear, and exact description thereof.

The invention relates to a support for drawers of cabinets, filing cases, etc., its object being to provide a simple and effective form of the device by means of which the drawers are held in a rigid horizontal position when withdrawn from the cabinet, and so limited in their outward movement as to prevent their dropping when drawn out to full extent.

The invention comprises the novel features hereinafter set forth and claimed.

In the accompanying drawing Figure 1 is a vertical section of the upper part of the cabinet with a drawer in elevation partly withdrawn, dotted lines showing the drawer fully pulled out and in position to be disengaged; Fig. 2 is a section on the line 2--2, Fig. 1; Fig. 3 is an interior view of one of the sides showing the drawer withdrawn.

In the drawing the numeral 2 designates a portion of a cabinet, filing case or the like, provided with drawers 3. Secured to the inner walls of the casing are the channels 6 which form guide ways for the sliding Z-bars 7. These Z-bars are cut away for about half of their forward portion as indicated at 9. Secured to the Z-bars at their rear portions are the wheels or rollers 10 which are adapted to engage the channels 6 and move back and forth therein. Secured to the inner ends of said Z-bars are the plates 11 which carry the buffers 12 adapted to engage the stops 13 on the inner walls of the cabinet.

Secured to the cut-away portions 9 of the Z-bars 6 are the wheels 14. Secured to the outer walls of the drawer are the channels 15 which are adapted to receive the wheels 14 mounted on the outer end of the Z-bars, said channels moving freely over said wheels. At the outer ends of the Z-bars are the stops 17 which project up in the path of the mov-

able blocks or buffers 18 on the outer walls of the drawer. These blocks 18 are made movable so that they may be moved, or lifted, out of the path of the projections 17 at the outer ends of the Z-bars to permit of the entire withdrawal of the drawer or its disengagement from the suspension device or Z-bars. Any suitable manner of securing these blocks in position so as to be drawn out of the path of the projections on the outer ends of the Z-bars may be employed. We have illustrated a simple form in which the block or buffer 18 is mounted on a slide 19 which is adapted to move up and down in the guide strip 20 secured to the drawer.

From the above construction, when the drawer is in its closed position and it is desired to withdraw the same, the operator grasps the drawer by the handle in front and withdraws the same, the channel-bars 15 on the said drawer moving freely over the wheels 14 on the Z-bar until the blocks or buffers 18 come in contact with the projections 17 on the Z-bars, whereupon by further withdrawal of the drawer the Z-bars are withdrawn, moving freely in the channel bars 6 on the inner walls of the case. The drawer can thus be withdrawn until the buffers 12 on the plates 11 on the inner ends of the Z-bars strike the stops 13, whereupon a further withdrawal of the drawer is prevented. The drawer, when withdrawn in this position stands in a rigid horizontal position and there is no liability of its sagging, or being entirely withdrawn so as to drop to the floor, as the buffers 18 are also in contact with the projections 17 on the outer ends of the Z-bars. If it is desired, however, to remove the drawer entirely it is only necessary to draw up the slides 19 carrying the buffers 18, whereupon the drawer is free to be lifted or removed from the suspension device.

What we claim is:

1. In a device of the character described, the combination of a suitable cabinet, filing case or the like, guides on the inner walls of the same, a drawer, Z-bars slidable in said guides, wheels on said Z-bars, channel bars on said drawer with which said wheels engage, stops in the path of said Z-bars, and stops on said Z-bars with which said drawer comes in contact.

2. In a device of the character described,

the combination of a cabinet, filing case or the like, guides on the inner walls of the same, a drawer, Z-bars, wheels on said Z-bars movable in said guides, stops in the path 5 of said Z-bars, channel bars on said drawer, wheels on said Z-bars engaging said channel bars, stops on said Z-bars with which said drawer comes in contact.

3. In a device of the character described, 10 the combination of a cabinet, filing case or the like, guides on the inner walls of the same, a drawer, Z-bars with their forward portions cut away, wheels on the rear portion of said Z-bars movable in said guides, 15 stops for said Z-bars, wheels on the forward

portion of said Z-bars, channel bars on said drawers with which said last named wheels engage, and stops on said Z-bars with which said drawer comes in contact.

In testimony whereof, we the said JOHN 20 D. RIPSON and ERICK G. SAMPSON have hereunto set our hands.

JOHN D. RIPSON.
ERICK G. SAMPSON.
